United States Patent Office.

AARON P. RICH, OF TROY, NEW YORK.

Letters Patent No. 66,992, dated July 23, 1867.

IMPROVEMENT IN MACHINERY FOR FITTING UP STOVE-PLATE PATTERN BOILER-HOLE SEATS.

The Schedule referred to in these Letters Patent and making part of the same.

TO ALL WHOM IT MAY CONCERN:

Be it known that I, AARON P. RICH, of Troy, in the county of Rensselaer, and State of New York, have invented a new and improved Machine for "Fitting Up" Stove-Plate Pattern Boiler-Hole Seats; and I do hereby declare that the following is a full and exact description of the same, reference being had to the annexed drawings and to the letters of reference marked thereon, forming a part of this specification, in which—

Figure 1 is a perspective view of said improved machine.

Figure 2 is a vertical sectional view of fig. 1, taken through its centre part, the blue shaded line thereon showing the manner of "bedding" a boiler-hole stove-plate for the purpose of operation thereon; and

Figure 3 is a detached view on an enlarged scale of the rotating tool-holder or cutter-head, the blue shaded line theron representing a boiler-hole cover or lid, as secured in position to be "trued up" or fitted.

The same letters refer to like parts in each of said figures.

In "fitting up" or finishing iron patterns for cooking-stoves and ranges, such as are used by moulders in preparing moulds for castings of the same for stoves and ranges, the boiler-hole seats or flanges in said patterns have been fitted for such use heretofore by the slow and expensive process of filing and scraping them by hand labor, and the degree of accuracy of such method of fitting and finishing depended entirely upon the manual skill and dexterity of the workman engaged, making such process necessarily wanting in perfection, expedition, and in economy. To lessen the expense and make perfect the fitting and finishing of such parts of iron patterns as above mentioned is the object of my said invention, which is the production and construction of a new and improved machine to fully perform and accomplish the work of "fitting up" the boiler or pot-hole seats in stove-plate patterns, and also to accurately fit the lids or cover-patterns to said boiler-holes, which process is performed by the operation of said machine in an accurate, expeditious, and economical manner. Said improved machine is also applicable to, and intended to be also used for, "truing up" boiler-hole seats, and their lids or covers, in castings for first-class cooking-stoves, previous to mounting the same.

The nature of my said invention and improvements consists in a rotating tool-holder, having a suitable feed motion given to it, and its shaft passing through a bed-plate, substantially, so as to be supported by said bed-plate, to prevent lateral springing of the shaft when the cutting-tool acts; and employing it in combination with a slotted bed-plate, circumjacent adjustable bearing or bed-screws, adjustable stay-pieces, and adjustable set-screw clamp-pieces; the said parts being employed, combined, and arranged with said tool-holder, in manner substantially as hereinafter fully described, and for the purposes of the better "bedding" of and "reaming out" or "fitting up" stove-plate pattern boiler-hole seats. The boiler-hole plates of stoves being thin castings, with deep flanges around the boiler holes and at other parts of the under surface of the plate, which, together with deep border mouldings, made such plates difficult to bed firmly and equally, so as to be operated upon without "springing" or fracturing them, and to prevent such liability, it has been the practice heretofore to "bed" such plates by driving a series of blocks or wedges, or "wedging up," between the bed-plate and those parts of the plate not touching the bed-plate, but which require a solid bed. This method of "wedging up" is defective in practice, for, owing to the lightness of stove-plates, the least tremors or shakings of the plate by action of the cutting-tool on it would loosen and displace the wedges from their adjusted positions, which loosened the support to that part of the plate directly acted on, thereby incurring liability to fracture or "springing" of the plate, besides spoiling the accuracy of the work. But by my said improvements the aforementioned plates can be quickly adjusted, and solidly, equally, and immovably "bedded," in manner substantially as hereinafter shown, so that such plates may be acted upon by a cutting-tool without at all deranging the "bedding" devices, as is the case when blocks or wedges are employed.

To enable others skilled in the art to make and use my said invention and improved machine, I will now proceed to fully describe its construction and operation, to wit:

Within a stout framework of timber or of iron, A A, B B, and C, is the bevel gear-wheel F and its connecting pinion-gear E, arranged substantially in manner as shown in the annexed drawings. Upon the shaft H of said bevel-gear is arranged a hand-wheel, G, which operates by means of the usual devices employed for that purpose, and well known to machinists, to feed a cutter-head or tool-holder attached to the top end of said shaft, either up or down, as may be desired. Secured to the top of the aforesaid framework is a bed-plate, D,

provided on each side or end with a series or set of diagonally-located slots or openings, P P. The inner ends of each set of said slots, at each, respectively, opposite sides of the bed-plate, converge toward each other, or have diagonal positions to each, in manner substantially as shown in fig. 1. Arranged to be adjusted to any position on and over said slots P P are clamp-pieces L L, and being respectively secured in adjusted positions by means of a bolt passing through said slots and secured by a nut, b. The horizontal arms of said clamp-pieces are respectively provided with a set-screw, R; also, arranged on and over either the first or second adjoining slots P are stay-pieces M M, which may be adjusted to any desired position on or along said slots, and secured therein by means of a bolt passing through the slot and stay-piece, and held by a nut, a. Arranged around and passing through the bed-plate D, and adjustable therein, is a series of bearing or "bed" screws, q q q, and provided with check-nuts, substantially as shown in figs. 1 and 2. K is a removable tool-holder, holding a tool, h. This is used only when "truing up" and fitting boiler-hole covers or lids, and it is then placed in proper position upon the bed-plate D, so as to have its tool come in cutting range of a cover "bedded" upon the flanged top of tool-holder J, and it is secured in such position to the bed-plate by bolts and nuts, as shown. The upper part of aforesaid shaft H passes through the bed-plate D, and it is thereby, with its cutter-head, fully supported or braced, and prevented from lateral "springing" when in action. To the top part of this shaft is keyed a tool-holder or cutter-head, J, which is recessed in its top side to form a chamber for the cutting-tool s, that projects its cutting point or edge through an aperture in the side of said recess or chamber, said tool being adjusted to its work by a set-screw, f, passing through the side of the recess, and held in adjusted position by a set-screw, g. The upper part of said tool-holder J is made with a flange or rim, c, which has notches for holding fastening-down bolts d d; and also a set of adjustable bearing or "bed" screws, e e, is provided, having check-nuts to secure them firmly in adjusted positions. N is a crank for operating the machine. In place of the crank a pulley may be used, and the machine operated by steam or other power.

The operation of this improved machine is as follows: To "fit up" stove pattern-plate boiler-hole seats, the plate or casting is first properly adjusted on the bed-plate D, so that the cutter-head or tool-holder J is centred within one of the boiler holes. The plate is then firmly secured in such position by adjusting the stay-pieces M, up in the slots P, to the corner edges or thereabouts of the border moulding of the plate, and securing them therein by their bolts and nuts a. The clamp-pieces L are then adjusted up in their slots P to the opposite edges, and then tightened by their bolts and nuts b, thus preventing either any side or any end play or movement to the said stove-plate. The set-screws R in the arms of the said clamp-pieces are now "set" down to the plate, thereby preventing any upward movement of it. It being necessary, in such large and thin castings as stove-plate tops or boiler-hole plates, that those parts directly operated upon be solidly supported, and to give such support to a boiler-hole flange, which in many cases does not touch the bed-plate D, it being prevented therefrom by the width or depth of the border-moulding of the plate, to meet such cases the adjustable bearing or "bed" screws q are provided, which, being "set up" to the boiler-hole flange and so secured by check-nuts, give thereby a firm bearing, that permits said boiler-hole seat to be turned out or "fitted up" by the rotating-tool or cutter s, when the aforesaid tool-holder J is rotated, without liability of "springing" or fracturing the casting; all in manner substantially as shown by the blue shaded section of a stove boiler-hole plate in fig. 2 of annexed drawings. To "fit up" boiler-hole lids or cover patterns, the boiler-hole plate is first removed from the bed-plate D, and the cover casting is then centred or adjusted on the top or face side of the cutter-head J. It is then bolted, through holes previously drilled through it, to the flange c, thereby firmly holding it to said flange; and if the cover is "sprung" or warped any in casting, so that it does not bear on evenly and equally all around the flange, as is sometimes the case, then the adjustable "bed" screws e are "set up" to those places not touching the flange, and so secured by check-nuts, thereby making a firm bearing all around to support the edge parts of the cover. The removable tool-holder K, with its tool h, is now adjusted in proper position for action upon the cover, and so secured by bolts and nuts to the bed-plate D. The machine being now put in operation, the cover is rotated in contact with tool h, and is thus "fitted" and "trued up." The manner of "bedding" a cover to the aforesaid cutter-head J is shown by the blue shade line in fig. 3.

What I claim as my invention, and desire to secure by Letters Patent, is—

I claim the employment of a rotating tool-holder, J, having a vertical feed motion, and its shaft H passing through a bed-plate, in manner substantially as set forth, in combination with circumjacent adjustable bearing or "bed" screws q, and a slotted bed-plate, D, with adjustable clamp and stay-pieces, substantially in manner as herein described, and for the purposes set forth.
